(57) **CLAIM**

The ornamental design for a guitar headstock, as shown and described.

DESCRIPTION

FIG. 1 is bottom-front-left perspective view of a guitar headstock in accordance with the present design;

FIG. 2 is a left-side view of the headstock of FIG. 1;

FIG. 3 is a right-side view of the headstock of FIG. 1;

FIG. 4 is a front view of the headstock of FIG. 1;

FIG. 5 is a rear view of the headstock of FIG. 1;

FIG. 6 is a top view of the headstock of FIG. 1; and,

FIG. 7 is a bottom view of the headstock of FIG. 1.

The broken lines represent the portions of the guitar headstock that form no part of the claimed design.
